(57) **CLAIM**

The ornamental design for an electronic device, as shown and described.

DESCRIPTION

FIG. 1 is a bottom-left-front perspective view of an electronic device, showing our new design, according to a first embodiment thereof.

FIG. 2 is a front elevational view of the first embodiment thereof.

FIG. 3 is a right side view of the first embodiment thereof.

FIG. 4 is a left side view of the first embodiment thereof.

FIG. 5 is a top plan view of the first embodiment thereof.

FIG. 6 is a bottom plan view of the first embodiment thereof.

FIG. 7 is a rear elevational view of the first embodiment thereof.

FIG. 8 is a bottom-left-rear perspective view of the first embodiment thereof.

FIG. 9 is a bottom-left-front perspective view of an electronic device, showing our new design, according to a second embodiment thereof.

FIG. 10 is a front elevational view of the second embodiment thereof.

FIG. 11 is a right side view of the second embodiment thereof.

FIG. 12 is a left side view of the second embodiment thereof.

FIG. 13 is a top plan view of the second embodiment thereof.

FIG. 14 is a bottom plan view of the second embodiment thereof.

FIG. 15 is a rear elevational view of the second embodiment thereof; and,

FIG. 16 is a bottom-left-rear perspective view of the second embodiment thereof.

The broken lines indicate environment and forms no part of the claimed design.

1 Claim, 14 Drawing Sheets
